MEANS FOR ATTACHING STOVES TO SHIPPING CRATES

Application filed October 10, 1931. Serial No. 568,169.

This invention relates to a stove leg and shipping crate interlocking means for a stove and has for its general object to cut down shipping costs.

5 Stove manufacturers have always been much concerned over the relative high crating and shipping costs which they must bear incident to the shipment of their relatively heavy products, and are constantly seeking 10 improvements which will enable them to reduce such costs. Heretofore it has been the practice to employ as many as eight hook bolts for the purpose of securing the stove body to the shipping crate, which bolts of course are never returned to the manufacturer. This item is of considerable importance to large manufacturers who ship thousands of stoves in the course of a year. To render this costly use of hook bolts unnecessary, the 15 20 stove leg attaching bolts of the present invention have been so designed and mounted as to permit of their use for shipping purposes, thus displacing the hook bolts heretofore employed. These leg attaching bolts 25 are necessarily of very heavy and strong construction and consequently are capable of doing double the work of the separate hook bolts heretofore employed solely for securing the stove in the shipping crate. Consequen- 30 tly, a saving of eight bolts is effected on each shipment of the stove. As previously explained, it is customary for stove manufacturers to remove the legs from the stove body before shipment to a dealer, who assembles 35 these parts. Therefore, the use of the leg attaching bolts for securing the stove in a shipping crate does not entail extra labor on the part of either the manufacturer or the dealer. In fact the use of four bolts where as many 40 as eight had been used heretofore, effects a saving both in assembling, disassembling, and in crating and uncrating.

In the accompanying drawings forming 45 part of this specification, Figure 1 is a perspective view of a shipping crate with a range attached thereto according to the invention. Figure 2 is a section through one corner of the stove and the crate showing the attachment of the stove to the crate by a single bolt. 50 Figure 3 is a perspective view of a gas stove

or range, and Figure 4 a sectional view through one of the corners of the gas stove of Figure 3 showing the attachment of the leg by a single bolt. Figs. 5, 6 and 7 are perspective views of the front frame, side wall and the base frame respectively of the stove. Figure 8 is a sectional view on line 8—8 of Figure 2, and Figure 9 a sectional view on line 9—9 of Figure 4. Figure 10 is a perspective view of the bolt used for crating and attaching the leg of the stove.

Referring more particularly to the drawings S designates a stove or range comprising a body B supported by the usual four legs 6. Such legs are generally of more or less triangular shape and formed or provided with appropriately shaped top plates 7 for supporting the stove body at the four corners.

The base B of the stove comprises a rectangular angle iron base frame 9. The horizontal flanges 11 of base frame 9 are cut to permit bending of the vertical flange 12 thereof as at 12', to provide the four angles or corners of the base frame to which the legs are attached. The enameled rear and side walls 13 and front frame 14 of the stove body S are suitably secured to the base frame. In the case of the rear and side walls, connection is effected by bending the lower edges thereof to form horizontal flanges 15, which snugly engage and are bolted to the bottom faces of horizontal flanges 11 of the base frame 9, by means of bolts 16. The front frame 14 is secured to the vertical flanges 12 of the base frame by means of bolts or other suitable fastening means not shown.

When the stove is assembled, the four corners of the base frame thereof rest upon the top plates of the respective legs, and the latter are securely attached to the frame by means of headed bolts 20, which are permanently attached to and carried by the base frame. These bolts extend axially through the openings 21 in the upper end portions of the bends 12', which bends are produced in the operation of shaping the base frame angle member 9 into rectangular form. It is essential, as will presently be seen that the bolts 20 be permanently attached to the base frame,

so that they will always be available and in their proper place for assembly purposes, it being the practice for stove manufacturers to ship the stove and legs to their dealers disassembled, and of course they are fixed against displacement also in order to be available for use in attaching the stove base to the shipping crate. Withdrawal, or accidental displacement of the bolts from their hanging position in the openings 21, is obviated by making the heads 20' of the bolt 20 of elongated shape and of larger size than the openings 21. It will thus be seen that withdrawal is impossible because the heads of the bolts are too large to pass through the openings, whereas attempted withdrawal in the opposite direction causes the elongated bolt head to jamb against the inner face of front frame 14. Consequently, the bolts 20 cannot be removed without dismantling the body of the stove, or at least loosening the bolt connection between the front frame and the base frame. The lower straight threaded shank portions of the bolts 20 extend through openings 23 in the top plates of the legs and are provided with wing nuts 24 for securely clamping the top plate and base frame together. It should be noted that the leg attaching bolts 20 are of much greater length than would seem to be necessary for connecting the legs and body of the stove together. The purpose of employing long leg attaching bolts is to permit of their threaded ends extending through the brace boards of a shipping crate C sufficiently for the reception of the wing nuts.

After the legs have been removed from the stove body, the latter is placed in crate C with one end wall of the former resting on the bottom of the crate. This crate is especially designed for the purpose of this invention to the extent that top and bottom brace boards 26 are provided at one side of the crate in which bolt openings 27 are formed at predetermined points. These openings are so arranged that they will be in approximate axial alignment with the threaded ends of the bolts 20, and in position to receive the latter when the stove body is moved into proper position. The wing nuts 24 are then screwed home thus securely tying the four corners of base frame of the stove to the crate. All stresses and strains incident to handling and shipping of the crate are taken by that portion of the stove best adapted to withstand them, namely the base frame. It should also be noted that the bolts 20 form a permanent part of the stove and consequently are always in position for immediate use. While the bolts are pivotally mounted in the openings 21 to facilitate their insertion in the openings 23 and 27 respectively, formed in the top plate of the leg and in the crate, this movement is not sufficient for the bolts to move beyond the confines of the corners. When the bolts pivot-

ally move or are swung in one direction the threaded shanks of the bolts engage the inner faces of the respective angle iron base member, while under excessive movement in the opposite direction the elongated heads of the bolts engage the rear face of the front frame 14. Consequently, it will be seen that the bolts cannot be turned sufficiently far to become substantially out of alignment with the openings 27 in the crate.

What we claim, is:

1. In combination with a shipping crate, a stove body having a rectangular base frame, and a front frame attached to said base frame, fastening means pivotally interlocked with said base frame and permanently held in place by said front frame and connected to the crate.

2. The combination of a shipping crate with a stove body according to claim 1 in which the head of said hook bolt is of elongated form to limit the pivotal movement of said bolt.

3. The combination of a shipping crate with a stove body having a base frame and a front frame attached to said base frame, and a plurality of hook bolts pivotally and permanently attached to said body, the front frame being spaced from the base frame, and the hook bolts having elongated heads for engagement with the front frame in limiting the pivotal movement of the bolts.

In testimony whereof we affix our signatures.

CARL H. HOFFSTETTER.
ROBERT F. HOFFSTETTER.
